UNITED STATES PATENT OFFICE.

ALFRED GOETZ, OF BERLIN, GERMANY.

WINDING-FRAME FOR SMALL WARES.

1,151,580.

Specification of Letters Patent. Patented Aug. 31, 1915.

Application filed July 30, 1913. Serial No. 782,063.

To all whom it may concern:

Be it known that I, ALFRED GOETZ, a citizen of the German Empire, and residing at Berlin, Germany, have invented certain new and useful Improvements in Winding-Frames for Small Wares, of which the following is a specification.

The subject-matter of this invention is a winding-frame or winder for carrying small quantities of small wares sold in retail businesses.

Small wares of wool, cotton, silk, velvet and the like are placed on the market for retail sale, as is known, rolled in certain lengths on paper or board rollers. In this form, however, the small wares are but little suitable for making a pleasing, clearly arranged show, because a roller wound full with ribbon, tape or the like when considered purely outwardly is nothing striking to look at. In order to remedy these defects and more readily to arrange small wares in a small space and to show them more pleasingly and clearly, I provide according to this invention a winding-frame, on which the small wares are wound with a suitable number of turns.

I am aware that it is well known to wind articles in the form of a band or strip on winding-frames, but believe it is new to employ winding-frames for winding small wares of the above-mentioned kind in retail businesses of the branch of trade in question.

In order completely to attain the end in question, according to my invention the winding-frame is made of sheet-metal, preferably aluminium.

Two illustrative embodiments of my invention are represented by way of example in the accompanying drawing, wherein:

Figure 1 is a perspective view showing a preferred form of my winding frame; Fig. 2 is a like view showing one end of another form, and Fig. 3 is a detail view showing the separated parts of the frame shown in Fig. 2.

Referring to Fig. 1, the winding-frame *a* comprises a flat piece of sheet-metal, preferably aluminium, provided at both ends with prongs or lugs *b*, *b*¹, some of which are fixed and some hinged. Two bulged portions *c*, *c* formed by cuts in the middle of the frame and by portions of the metal being bulged outward constitute bearings through which a pin or axle *d* can be placed in order to mount the winding-frame in a stand for

winding up or unwinding the small wares *e*, so that the axle can rotate with the frame, which, of course, must be firmly held on the axle. By stamping a hole *a*¹ in the frame I provide that the frame always adjusts itself into the vertical plane, as the solid portion *a*² of the frame acts as a weight.

An elastic cord *f* or other elastic tie is attached in the prongs *b*, *b*¹ at one or both sides of the frame. This elastic has a length which corresponds approximately to the distance between two prongs and terminates in a knot or button *f*¹. By means of this knot or button *f*¹ the elastic *f* is held in one of the notches *g* provided in the opposite prong *b* and a certain tension is given to the elastic; this tension is increased or diminished according as the distance between the point of attachment of the elastic in the one prong and the point of attachment in one of the notches in the other prong is increased or diminished, and the tension of the elastic can be regulated in this manner.

The object of the elastic cord is to secure the upper or outside end of the small wares or ribbon *e* wound on the frame *a*. If the frame is wound full so that a large number of turns of the ribbon *e* are located on it, the tension of the elastic *f* must not be too great owing to the considerable depth of the roll, because it would otherwise produce strong impressions in the small wares or ribbon and the good appearance of the latter when unwound would be impaired. Accordingly, the one end of the elastic will be held in a notch *g* nearer to or more remote from the point of attachment of its other end according to the quantity of the ribbon *e* wound on the frame, in order in this manner to regulate the tension of the elastic and its pressure on the outer end of the wound ribbon.

The prongs *b* and *b*¹ are held in their extended position, and in any adjusted position, by frictional contact. The tension of the elastic core *f* is not sufficient to overcome the frictional contact of the prongs *b* and *b*¹ therefore the cord *f* will not have an tendency to move the prongs *b* and *b*¹ from their normal or adjusted positions.

In order to prevent the wound-up ribbon, and particularly its first inside turns at the ends of the frame from pressing too severely on or being cut into by the very narrow edges of the plate *a* between the prongs *b*, *b*¹, whereby very ugly bends or uneven

places would be produced in the ribbon, particularly in the first turns thereof, the edges of the frame *a* between the prongs are rounded or, as shown in the drawing, turned 5 over to form beads *i*. Owing to these beads sharp bends in the ribbon where its direction changes are avoided with certainty.

Referring now to Figs. 2 and 3, in this embodiment the beaded edge *i* is formed as a 10 hollow roll or bearing for containing a pin or pivot *k*. Two lugs or prongs *b*¹ separate from the frame *a* are mounted on the ends of the pin *k*, and owing to the latter rotating without play in the bead *i*, the prongs can 15 be turned from the position shown through 180° in a plane at right angles to the plane of the frame, whereupon the ribbon can be slipped laterally off or onto the frame, which is possible in the form according to Fig. 1 20 when the prongs *b*¹ are rotated into the position indicated in dotted lines.

Owing to the winding-frame being made of sheet-metal, preferably sheet aluminium, it has sufficient stability to enable it to be 25 placed when fully wound with small wares in a vertical position and to be secured therein, in order to show the small wares as effectively as possible to the observer. This property is entirely lacking in the winding- 30 frames made of cardboard or pasteboard heretofore employed for holding small wares, while winding-frames made of wood are too thick and heavy for the purposes in question, and also suffer under the action of 35 moisture and warp, which is quite impossible in the case of metal winding-frames.

I claim:—

1. A winding frame comprising a main

body on which material may be wound for 40 display, and a pair of prongs extending from each end of the body, one prong of each pair being adapted to be rotated to a position along side of the edge of the body whereby the said material may be slipped 45 off said body.

2. The combination of a sheet-metal winding-frame having forked ends, one of the prongs of one forked end having notches in the side thereof, and an elastic tie having one end attached to the other prong at the same forked end and adapted to be fastened at its other end in one of said notches. 50

3. The combination of a sheet-metal winding-frame having beaded ends constituting 55 bearings for the material to be displayed and a fixed prong at the one end of each bearing, an oscillatable prong and a pin, carrying said oscillatable prong, rotatably held at the other end of each bearing.

4. The combination of a sheet-metal winding-frame having forked ends directed away 60 from each other, one prong on each fork being revolvably mounted so that the prongs will fold in a direction toward each other and outwardly-bent portions constituting bearings in the middle thereof, and an axle carried in said bearings, the part of the frame at the one side of the axle being materially 65 heavier than the part thereof at the other side.

In testimony whereof, I affix my signature in the presence of two witnesses.

ALFRED GOETZ.
